DROP FOOT BRACE

Lillian M. Goffredo, New York, N. Y.

Application January 10, 1948, Serial No. 1,502

1 Claim. (Cl. 128—80)

1 This invention relates to improvements in braces for weakened feet.

Many types of foot supports or braces have heretofore been devised and used. The two most commonly used today are the full length leg brace which extends from the hip to the foot and the half length leg brace which extends from just below the kneecap to the foot. These braces, however, are embarrassingly conspicuous, especially when worn by women, and they are extremely uncomfortable to wear. Furthermore, they are difficult to put on and take off and they unduly restrict the wearer's movements. These leg braces are also quite expensive and they are generally unsatisfactory for the purpose for which they are intended.

The principal object of the present invention is the provision of a foot brace which combines all of the advantages which the leg braces above referred to lack, and which possesses none of their disadvantages and shortcomings. Although the present device and those above mentioned constitute foot supports or lower leg supports, these other devices extend the full length of the leg or at least half its length. The present device, on the other hand, occupies but a small portion of the lower leg. It is therefore much smaller and lighter than the previous devices and consequently relatively inconspicuous and more comfortable to wear. The construction of the present device is exceedingly simple, and it is accordingly relatively inexpensive to make. Its very simplicity of construction also makes for ease of application to the foot, and it may be put on the foot and removed from the foot without the slightest difficulty. A very decided benefit and advantage which necessarily flows from the fact that the present device covers but a small area on the lower leg is the freedom from restriction of movement of the wearer, which it affords. It is in the full sense of the word "a support" rather than a brace, and it contributes to the wearer's ability to move about. Far from making a corresponding contribution, the prior art braces hereinabove referred to actually restrict and limit the wearer's freedom of movement. To illustrate this point, it may be mentioned that where the patient has the ability to "lock" his knee although both foot and leg are weak, use of a half-leg brace or of a full-length brace would cause a pull on the leg or knee, whereas the use of the present device would lend adequate support to the weakened foot and leg without pulling upon the leg or knee.

A preferred embodiment of this invention is shown in the accompanying drawing in which

2 Fig. 1 is a perspective view of the device herein claimed, showing it worn on the lower leg; and

Fig. 2 is a plan view of said device, showing it spread out flat.

It will be seen in the drawing that the present device comprises an ankle strap 10, which may be made of cowhide leather or other suitable material, approximately two to three inches in width and of a thickness which is dictated by the strength and stiffness of the material used. It is lined with a soft material 11, such as kidskin or any other soft leather. This lining extends the full length and width of strap 10, and it is also folded over its edges, as shown in the drawing. This design provides a soft edge to the strap and renders it easier to wear. The lining is affixed to the strap by means of stitches 12 which extend marginally of said strap on all side edges thereon. Riveted or otherwise affixed to one end of the strap 10 is a pair of smaller straps 15. Affixed to the opposite side of strap 10, also by means of rivets or other conventional means, is a pair of buckles 16. Straps 10 are divided with a plurality of buckle-engaging holes 17, and it will be understood that when the strap 10 is placed upon the ankle as shown in Fig. 1, it may be held in place thereon by means of apertured straps 15 which engage the buckles 16. It is by this means that strap 10 may be applied to the ankle with any degree of tightness. It may also be adjusted by this means to ankles of different sizes and proportions.

Intermediate the straps 15 and the buckles 16 is a looped member 20 which may also be affixed to the strap 10 by rivets or any other conventional means. It will be seen in Fig. 1 that a tie member 21 may be used to attach the strap 10 to shoe 22 worn by the wearer of strap 10. This tie member which should be made of a resilient or elastic material, such as rubber tubing, may be drawn through the lower eyelets 23 of shoe 22 and then drawn through a ring 25 which loop 20 supports, and said tie member may be tied to said ring 25 in any desired manner. The tightness of the connection between the strap member 10 and the eyelets of the shoe 22 and the elasticity of the tie member 21 will determine the amount of support which the device will give to the weakened foot.

It will be understood that the foregoing is a description of a preferred embodiment of this invention and said embodiment may be changed to accord with different requirements within the broad scope and spirit of the invention. For example, the tie member may be made longer or

shorter, depending upon the foot and ankle dimensions and upon the weakness of the foot or anterior tibia or both. It may also be made of greater or lesser elasticity. It may be made of rubber tubing or rubber strands or strips or of any other corresponding material. The strap 10 may be made wider or narrower as desired or required, and it may be made longer or shorter, depending upon the individual need of the wearer. It may be made of leather as has heretofore been indicated, or of a plastic or woven material, and it may be made stiffer or more yielding as desired. Other means than the ring 25 may be used to affix the tie member to the looped member 20. Other modifications will suggest themselves to those skilled in the art. 15

I claim:

Foot supporting means, comprising, the combination with a shoe having lace eyelets at the front thereof, a removable ankle band, an elastic 20

lace passing through at least one of said eyes, and a ring freely supported in a loop on the front of said ankle band adapted to have the ends of said elastic lace adjustable tied thereto.
